UNITED STATES PATENT OFFICE.

ALBERT T. KELLER, OF BETHLEHEM, PENNSYLVANIA, ASSIGNOR TO BETHLEHEM STEEL COMPANY.

MANUFACTURE OF STRUCTURAL UNITS.

Application filed March 15, 1926. Serial No. 94,740.

My invention relates to improvements in the manufacture of steel or iron beams, girders, bars or other structural pieces or shapes having heads or flanges and pertains 5 more particularly to improvements in producing an I or H beam of comparatively thin cross section compared with beams of standard cross section.

When the metal of the flanges is rolled 10 relatively thin it does not flow uniformly, the marginal edges become waved and it has been found difficult in commercial practice to obtain straight flange edges along the length of the beam with the usual type 15 of edging rolls of the universal mill or the edging surface of the closed pass of the standard mill. Furthermore, the thin marginal edges cool rapidly, are quickly chilled and as the portions of the rolls which are 20 in contact with the edges move at a slower speed than the metal and consequently the chilled edges, having lost their plasticity, are torn or broken.

The object of my invention is to provide 25 a method for rolling shapes of unusually thin cross section, suitable for joists in building construction.

In its general aspect, my invention comprehends a method of rolling structural shapes of unusually thin cross section, 30 wherein the flanges are rolled wider than the desired width in the finished article, and finally sheared to finished dimensions.

In the accompanying drawings,

35 Figs. 1 and 2 are side elevations of the rolls showing the passes for shaping the metal.

Fig. 3 is a side elevation of the rolling mill illustrating the preferred arrangement 40 of shearing machines.

Fig. 4 is a front view of the shearing machine with the beam in position.

Figs. 5, 6, and 7 illustrate types of structural shapes which may be produced by 45 practicing my invention.

Preferably I start with a bloom or billet 10, which in passing through pass 11, is provided with diagonally opposed flanges 12 and 13, and with somewhat shorter rudimentary flanges 14 and 15. The billet 10 is returned through the next pass 16 in 50 which the flanges 14 and 15 are flattened in the groove 17 and the flanges 12 and 13 are extruded into the groove 18. Hence it 55 will be seen that the flanges 14 and 15 are rolling the edges of the flanges in the supple-

widened somewhat more than the flanges 12 and 13. It will also be seen that the latter flanges are in grooves disposed out of normal relation to the axes of the rolls in the first pass and are formed by substantially 60 flat faces which taper or converge toward each other outwardly with an open space at the end of the pass. In the second pass the flanges 12 and 13 are in grooves normal with respect to the axes of the rolls and the metal of the flange is extruded laterally by the converging flat faces which form the groove, in contrast to the flattening action 65 of the faces in the flanges in the obliquely disposed passes aforementioned. Preferably the last mentioned grooves are of sufficient depth to allow for the unrestricted flow of the metal and do not confine the metal in a lateral direction. In the subsequent passes the flanges are alternately flattened and extruded, the beam being passed 70 backward and forward between the passes until the metal is reduced to the desired thickness. In pass 19 the web 20 is substantially 75 horizontal and the flanges are bent into proper position.

It will be seen with the above described method of rolling there is no edge rolling on the flanges. Other methods of rolling may be employed in practicing my invention, for 80 instance, I have found that by employing the method of rolling structural shapes disclosed in Letters Patent Reissue 16,097 issued June 16, 1925 to Henry Grey, I am 85 able to roll beams of unusually thin cross section of the type illustrated in Figs. 5, 6, and 7.

As previously mentioned, when rolling beams of extremely thin cross section it is very difficult to maintain a straight finished 90 flange edge acceptable to the building trade, the beam will usually have waved and defective flange edges, unless great care is exercised during the rolling operation. However, in accordance with my invention, the 95 flanges are rolled somewhat wider than desired and the marginal edges sheared to size. In this manner the defective metal at the edge of the flange is removed and the rolling operation does not need the care which 100 would otherwise be required to roll the flanges of thin shapes to finished size.

When practicing the aforementioned Grey method of rolling I may omit the step of 105 rolling the edges of the flanges in the supple-

mental rolls, and thus allow the unrestricted lateral flow of the metal so that the flanges draw out to a width to which the metal will flow during the successive rolling passes in 5 the universal mill.

After leaving the finishing pass, the beam is transferred to the shears 21 and 22, which are preferably placed in tandem as illustrated in Fig. 3. The shear 21 is arranged 10 to trim the upper flanges and the shear 22 acts on the lower flanges; the web of the beam being in vertical position as the beam passes through the shears. Only one shear may be employed and the beam passed twice 15 through the shear, first shearing one pair of flanges and then reversing the position of the flanges and shearing the other pair of flanges. A suitable guide (not shown) is provided to steady the beams in its central position while 20 passing through shears. I do not confine myself to any specific type of shear and in the preferred form of apparatus for practicing my invention I have illustrated a shear of the rotary type. The flanges of the beam 25 are fed between the overlapping edges of the shearing discs 23 which are positively driven by the motor 24 through the gearing 25.

From the foregoing description, it will be 30 seen that I have evolved a method of manufacturing structural units of unusually thin cross section which are suitable for use as metal lumber.

While I have shown my invention in but 35 one form, it will be obvious to those skilled in the art that it is not so limited, but is susceptible of various other changes and modifications without departing from the spirit

thereof, and I desire, therefore, that only such limitations shall be placed thereupon as are imposed by the prior art or as are specifically set forth in the appended claims. 40

Having thus described the invention, what I claim as new and desire to secure by Letters Patent is:

1. An improvement in the art of making 45 flanged shapes of predetermined size, consisting in forming the shape by rolling it with at least one of its flanges out of normal angular relation to the web, feeding the shape through a rolling pass or passes having at 50 least one of the flange forming grooves open, bending the flanges to normal position, the rolling being continued until the cross section is reduced to a considerable degree of 55 thinness and the flanges are appreciably wider than is desired in the finished product to eliminate the care necessary to produce perfect edges, and then shearing the flanges throughout their length to remove a portion 60 thereof thereby to produce perfect edges. 60

2. A process for manufacturing a flanged structural unit of predetermined size, comprising the steps of rolling a blank until its cross section is reduced to a considerable 65 degree of thinness and its flanges are appreciably wider than desired in the finished unit to eliminate the care necessary to produce perfect edges, and then shearing the flanges to the desired width and thereby to produce 70 a perfect edge. 70

In testimony whereof I hereunto affix my signature this 6th day of March, 1926.

ALBERT T. KELLER.
